UNITED STATES PATENT OFFICE.

LUDWIG KRAMER, OF CARLSTADT, NEW JERSEY.

DESIGN FOR RUCHING.

No. 39,379.

Specification for Design.

Patented June 23, 1908.

Application filed March 27, 1908. Serial No. 423,794. Term of patent 7 years.

To all whom it may concern:

Be it known that I, LUDWIG KRAMER, a citizen of the United States, residing in Carlstadt, in the county of Bergen and State of New Jersey, have invented a new, original, and ornamental Design for Ruching, of which the following is a specification, reference being had to the accompanying drawing, forming part thereof.

The drawing is a perspective view of a

short length of ruching, showing my new design.

I claim:

The ornamental design for ruching, as shown.

LUDWIG KRAMER.
